UNITED STATES PATENT OFFICE.

MURDOCK MACDONALD, OF CLEVELAND, OHIO, ASSIGNOR TO THE MACDONALD TICKET AND TICKET BOX COMPANY, OF CLEVELAND, OHIO, A CORPORATION OF OHIO.

REGISTER.

Application filed December 20, 1918. Serial No. 267,645.

To all whom it may concern:

Be it known that I, MURDOCK MACDONALD, a citizen of the United States, and a resident of Cleveland, county of Cuyahoga, 5 State of Ohio, have invented a new and useful Improvement in Registers, of which the following is a specification, the principle of the invention being herein explained and the best mode in which I have contemplated 10 applying that principle, so as to distinguish it from other inventions.

The present invention, relating, as indicated, to registers is particularly directed to certain improvements in that general type 15 of machines which are generally known as autographic registers, and which are used in shops and offices for conveniently and quickly writing out several duplicates of an order, receipt or other memorandum.

20 In such machines it is customary to provide two or more rolls of paper, from which the individual sheets are led to the top of the enclosed casing which is provided with an opening therein at one point and a supporting table beneath for the purpose of writing, and are then carried out from the machine to a straight-edge for tearing off the written tickets, orders or the like. Interposed between the superimposed sheets 25 of paper are sheets of carbon paper, which are usually brought permanently across the top of the supporting table and slide between the sheets of paper when drawn out. The difficulty in such machines is to keep 30 the superimposed sheets of paper in exact and permanent registration during their passage through the machine. Since the machines are all printed with certain memoranda it is of little real use unless the printing on the superimposed sheets is in exact 35 alignment at all times, as otherwise the carbon copies of the original sheet bear the written memoranda at the wrong place and opposite the wrong printed memoranda or 40 forms on the sheet. My improvements relate to an improved and simplified method of maintaining the superimposed sheets in registration their passage through the machine, and to certain other improvements 45 intended to simplify and make more convenient the construction and use of such mechanism. To the accomplishment of the foregoing and related ends, said invention, 50 then, consists of the means hereinafter fully

described and particularly pointed out in 55 the claims.

The annexed drawing and the following description set forth in detail certain mechanism embodying the invention, such disclosed means constituting, however, but one 60 of various mechanical forms in which the principle of the invention may be used.

In said annexed drawings

Fig. 1 is a side elevation of my improved machine; Fig. 2 is a longitudinal section 65 through the left end of the machine as viewed in Fig. 1; Fig. 3 is a transverse section on the line 3—3, Figure 1; and Figure 4 is a longitudinal section through the handle and stop.

The general construction and arrangement of the machine is best illustrated in Fig. 1, and it is seen to consist of a suitable rectangular box-like enclosing casing 1, provided with two or more rollers 2, each carrying a roll of paper 3. From these rolls the sheets of paper 4, 5 and 6 are carried to the rear end of the machine and are then brought over small rolls or guides 7, from which they are carried in a superimposed 70 relation across the top of the machine, and across a longitudinally disposed support or table 8. The forward end of the machine, at the top 9 of the casing, is provided with an opening 10 of considerable extent directly 75 above one portion of the table 8, and at this point a user may write any desired memoranda upon the uppermost 6 of the three sheets 4, 5 and 6. The top 9 of the casing is hinged at 11 at the rear end of 80 the casing and may be swung upwardly in order to open the casing for the purpose of removing and replacing any of the paper rolls.

At the right side of the machine, as shown 95 in Fig. 3, there is formed an extension or small enclosing casing 12, in which are mounted a roll 13 carrying one or more sheets of carbon paper, from which roll the carbon paper is passed across the supporting table 8 and down on the outside of the machine where it is clamped by means of a hinged plate 15. This plate 15 is pivoted 100 to the outside of the casing at the point 16 and is received in a socket 17 at its other end 105 when brought to the carbon engaging position. Furthermore, the plate 15 is slightly beveled in order to snugly hold the edges

2
of the carbon sheets against the sides of the casing when the plate is in its locked position. A sufficient tension and grip is put on the carbon paper to hold it in the position indicated with each of the sheets of carbon paper between two of the sheets of paper from the rolls 3, and this relation is maintained even when the sheets of paper from the rolls 3 are carried forward by the mechanism to be presently described.

At the forward end of the machine there are mounted two co-operative corrugated rolls 20 and 21. The roll 21 is carried in suitable bearings in the sides of the casing proper and this shaft extends through one side of the casing and carries a crank arm 22 and handle 23 for rotating the two corrugated rolls to draw the paper between them and pass it out from the end of the casing. The other corrugated roll 20 is provided with extending ends 24, which are received in vertical slots 25 in a raised extension 26 on the forward end of the cover 9, and this roll is maintained in resilient but steady contact and engagement with the roll 21 by means of springs 27 which press down upon the shaft ends or spindles 24.

The handle 23, for operating the corrugated rolls, includes a spring pressed plunger 28 which is normally maintained in the position shown in Fig. 4 by a coil spring 29, and in this position is pressed inwardly toward the casing and in a position to engage a stop 30 projecting from the side of the casing, which normally prevents movement of the handle in a direction to operate the rolls 20 and 21 to pass the paper therebetween.

The lower roll 21 is also provided with ratchet teeth 31 and a pawl 32, which prevent operation of the rolls in such a way as to pass the paper forwardly between them. The cover 9 is locked in a position to operatively engage the rolls 20 and 21 with the sheets of paper therebetween by means of pivoted hooks 33 engaging over bolts 34 on the outer sides of the extension 26 of the top 9.

In operation the three sheets of paper 4, 5 and 6 are first passed forwardly over the supporting table 8 and under the cover 9. The carbon sheets are then brought between the sheets of paper and locked in position

by the plate or bar 15, and the paper is positioned over the lower roll 21. The cover 55 is then brought down into position and locked with the corrugated rolls in operative position. When the exposed portion of the sheets of paper are used the plunger 23 is pulled out, thus releasing its inner end 60 from contact with the stop 30, and the handle is given one complete revolution, the plunger being allowed to return to its normal position during that revolution so that it will engage against the stop 30 and limit 65 the action to exactly one revolution of the rolls 20 and 21. These rolls pass paper between them, maintaining the sheets in exact registration and alignment since the rolls grip and even slightly corrugate the paper 70 which is passed therethrough. The exposed portion of the sheets may then be torn off against the straight-edge 35 formed at the forward end of the cover 9.

The construction of the present register 75 is extremely simple and inexpensive, while the action of the co-operative corrugating rolls upon the paper prevents any possibility of any one of the sheets of paper lagging behind or slipping to one side and spoiling 80 the exact alignment of all the sheets.

Other modes of applying the principle of my invention may be employed instead of the one explained, change being made as regards the mechanism herein disclosed, provided the means stated by the following 85 claim or the equivalent of such stated means be employed.

I therefore particularly point out and distinctly claim as my invention:

In a device of the character described, the combination of a platen, a plurality of paper carrying rolls mounted to allow two super-imposed sheets of paper to pass over said support, paper feeding rolls disposed adjacent the end of said support, opposite that from which the sheets are fed, said paper feeding rolls provided with interengaging, longitudinally disposed corrugations having rounded surfaces to grip and fold 100 the sheets transversely their direction of feed only, thereby effecting uniform feeding of the sheets without mutilating the same.

Signed by me, this 19th day of December, 1918.

MURDOCK MACDONALD.
